UNITED STATES PATENT OFFICE.

HOMER H. DANIELS AND NELIE NAFUS, OF OSWEGO, KANSAS.

OIL-DISPENSING APPARATUS.

1,236,682.

Specification of Letters Patent. Patented Aug. 14, 1917.

Application filed November 26, 1915. Serial No. 63,577.

To all whom it may concern:

Be it known that we, HOMER H. DANIELS and NELIE NAFUS, citizens of the United States, residing at Oswego, in the county of 5 Linn and State of Kansas, have invented certain new and useful Improvements in Oil-Dispensing Apparatus, of which the following is a specification.

Our present invention has relation to a 10 new and improved dispensing apparatus that is especially designed to be used in handling heavy machine oils in garages, etc.; the main objects thereof being to provide for the accurate measuring of the oil prior 15 to its dispensement and to afford facilities for discharging the same under pressure subsequent to the measuring operation.

Another object of the invention is to provide a device of this character which occupies 20 the minimum amount of floor space, consistent with its satisfactory operation.

Another object is to provide a device of this character whereby the mechanism thereof and the oil dispensed thereby is effectively protected from dust and other foreign 25 matter.

A further object of our invention is to provide a device of the type in question that is extremely simple in construction, strong 30 and durable, and highly practical both from the standpoint of the manufacturer and the standpoint of the user; and which, it is believed, may be manufactured at a comparatively low cost.

35 Various other objects and advantages will become apparent during the continuance of the following description.

These objects are accomplished by such means as are shown in their preferred form 40 in the accompanying drawings, described in the following specification and then more specifically pointed out in the appended claims.

In the accompanying drawings wherein 45 like characters designate like parts throughout the several views:

Figure 1 is a view in side elevation showing my invention as in its preferred embodiment; the storage tank being shown buried 50 in the ground while the dispensing apparatus is mounted in the usual manner.

Fig. 2 is a view in vertical section illustrating in detail the supporting stand and the dispensing apparatus.

55 Fig. 3 is a fragmentary view of the dispensing apparatus.

In reducing our invention to practice, we provide a suitable stand 10 that is preferably constructed of metal and provided with a hinged door 11 whereby access may be had to its interior and whereby dust and grit are excluded from the oil-receiving vessels 31 and 33. At its upper end, the stand 10 is constructed so as to be capable of receiving a compression cylinder 12, the latter being provided with an annular supporting flange 13 to rest upon the enlarged portion 14 of the stand, as clearly shown in Fig. 2. A weighted plunger 15 is arranged to operate within the cylinder or dispensing 70 chamber 12 and is preferably constructed in a manner whereby it will form a comparatively fluid-tight connection with the interior side wall thereof, and at the same time provide for the discharge of the contents of the cylinder under pressure, such as will be subsequently pointed out. Although as above stated the walls of the plunger form a comparatively fluid-tight connection with the inner periphery of the cylinder it 80 is deemed expedient to employ a packing ring 16, that may be arranged in the manner shown so as to further assure the fluid-tight connection.

A series of standards 17 extend through 85 the supporting flange 13 of the cylinder and the adjacent projecting flange of the packing ring so as to adequately support a plate 18 in spaced relation to the upper end of the cylinder. Any suitable means may be employed to retain the plate in position on the standards; however in the drawings we have shown a plurality of nuts 19 for accomplishing this purpose. This plate is designed to support a registering indicator such as indicated by the numeral 20 that carries a depending actuating rod 21 to be raised by the plunger 15 during its upward movement. Consequently it will be recognized that the quantity of fluid in the cylinder may be 90 readily ascertained by referring to the indicator 20; the latter of course registering in 95 consistence with the height of the plunger 15 with respect to the cylinder.

In order to exclude foreign material from 100 the working parts of the apparatus and at the same time to permit the numerals of the indicator 20 to be readily viewed by the operator, a globe 22 may be arranged there-over and supported by the annular ledge 23 110 of the supporting flange 13. The globe is of course preferably constructed of glass.

At its lower end the cylinder 12 has connection with a three-way valve comprising a valve casing 24, the latter accommodating a valve member 25 that is designed to establish communication between certain of the passage ways 26, 27 and 28, at different times so as to provide for the proper dispensement of the material being handled. An operating handle such as indicated by the numeral 29 may be associated with the valve in the manner shown in order to facilitate the proper actuation thereof.

Within the body 10 at a point appreciably below the door opening we arrange a suitable bracket 30 for supporting a drip pan 21 while a bracket 32 may be arranged immediately adjacent the opening so as to support a container such as indicated by the numeral 33 that is to receive the fluid from the cylinder. It will be appreciated that the material overflowing the container 33 will fall into the drip pan 31 where it may be collected and returned to the storage tank.

The storage tank 34 is preferably sunk into the ground in the usual manner and provided with an upstanding pipe 35 through which it may be refilled. It is of course desirable to provide a cap 36 to normally close the upper end of the pipe 35 and thus exclude foreign matter from settling into the tank. The tank 34 may be also connected with a compressed air line, such as indicated by the numerals 37 and 38 whereby air may be introduced into the same for forcing the oil through the outlet pipe such as will be presently described. A controlling valve 39 is of course associated with the air line 38 so as to regulate the supply of air entering the tank, while an indicator 40 may also be employed so that the air pressure may be readily ascertained. Furthermore a safety valve 41 may also be arranged in connection with the air line so as to relieve the pressure in the tank and thus guard against the straining and consequent bursting thereof.

The tank is further provided with an outlet pipe 42 whose inner end terminates at a point only appreciably above the bottom thereof, while its other end has connection with another pipe 43, exteriorly of the tank, such as shown at 44, while this latter pipe is in turn connected with the passage way 27 of the valve casing 24 by a pipe 45, as at 46. Consequently it will be seen that the contents of the storage tank may be forced through the pipes 42, 43 and 45 respectively directly into the cylinder 12 by way of the valve 25.

In the operation of our invention the air is of course introduced into the storage tank. However when this occurs the valve 25 may be moved to the position such as shown in Fig. 3 to prevent the entrance of the oil, or other material into the cylinder 12. Conse-

quently when desiring to dispense a predetermined quantity of the material, say for instance a half gallon, the operator moves the valve member 25 so as to establish communication between the passage ways 26 and 27 of the valve casing and thus permit the material from the storage tank to enter the cylinder 12. The material entering the cylinder under pressure will of course cause the elevation of the plunger 15 whereupon the latter will actuate the indicator 20. The operator, by referring to the indicator may ascertain when the desired amount of material has entered the cylinder whereupon the controlling valve may be again shifted to assume the position shown in Fig. 3 to close the passage way 27 and to establish communication between the passage ways 26 and 28 respectively. As soon as the pressure upon the material in the cylinder is relieved, the plunger 15 will of course have a tendency to return by gravity to its initial position thereby discharging the material under force through the respective passage ways and hence to the container 33. The weight of the plunger 15 may be varied according to the consistency of the fluid that is being handled *i. e.* increased when handling very thick oils, such for instance as heavy machine oil or the like, and decreased when handling material of a lesser consistency. The pressure exerted on the material that is in the cylinder greatly expedites the dispensement thereof in that it eliminates the slow flowing of the material such as would otherwise occur in the event that a material of heavy consistency was being handled.

From the foregoing it is believed that the advantages and novel features of our invention will be readily understood and therefore further detailed description is deemed unnecessary.

In reducing our invention to practice we find that the form referred to herein as the most practical and preferred embodiment is the most efficient but realizing that certain conditions will necessarily vary in concurrence with the adoption of our device, we desire to emphasize the fact that various minor changes in the details of construction and in the proportion of parts may be resorted to when required without sacrificing any of the advantages of our invention as defined in the appended claims.

Having thus fully described our invention, what we claim as new and desire to secure by Letters Patent is:

1. A liquid dispenser comprising the combination of a dispensing chamber having a bottom with a central opening therethrough and having a peripheral flange at its upper end, a vertically disposed tubular housing having its upper end closed by the flange of said cylinder, which flange is supported by said upper end, a support in said housing 130

- for supporting a receiving vessel, a plunger vertically movable within said chamber and operable to force liquid straight down into said receiving vessel and having its upper end protruding beyond the upper end of said chamber, an indicator operable by said plunger and supported above the top of said chamber, and a transparent shield supported by said flange and inclosing the said indicator and the upper end of said plunger and thereby allowing inspection of the operation of the said dispenser and its indicator.
2. An oil dispensing device comprising the combination of a dispensing chamber having an apertured and recessed peripheral flange at its upper end, a support on which said peripheral flange is seated, an indicator for indicating measurement of oil to be dispensed, means supported by said support and extending through the recesses and apertures of said flange for supporting said indicator above said dispensing chamber, an outlet port for said dispensing chamber, a weighty plunger movable vertically in said dispensing chamber and operable by its weight to force oil through said port, and means carried by said plunger for actuating said indicator.
3. An oil dispensing device comprising a dispensing chamber having a port at its lower end and having a peripheral flange at its upper end, a support upon which said peripheral flange is seated, a standard held in vertical position by said flange, an indicator supported by said standard, a weighty plunger movable vertically within and through the top of said dispensing chamber into contact with said indicator, for operating said indicator, and a transparent shield supported by said flange and covering said indicator and the top portion of said plunger.
4. An oil dispensing device comprising a dispensing chamber having a port at its lower end and having a peripheral flange at its upper end, a support upon which said peripheral flange is seated, standards supported by said flange, a member extending horizontally over said dispensing chamber and supported by said standards, an indicator supported by said member, a plunger movable vertically in and through the top of the said dispensing chamber and operable to force oil from the latter, means operated by said plunger for actuating said indicator, and means carried by said peripheral flange for protecting the top of said plunger and the said indicator from dust while allowing observation of said plunger and indicator, said member being effective for limiting movement of said plunger.

In testimony whereof we affix our signatures in presence of two witnesses.
